UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

REGULATOR SYSTEM.

Application filed September 16, 1918. Serial No. 254,220.

To all whom it may concern:

Be it known that I, FRANK CONRAD, a citizen of the United States, and a resident of Pittsburgh, in the county of Allegheny and State of Pennsylvania, have invented a new and useful Improvement in Regulator Systems, of which the following is a specification.

My invention relates to electric regulator systems and particularly to regulator systems for governing the excitation of generators in accordance with supply-circuit conditions.

One object of my invention is to provide a regulator system that shall be quickly responsive to voltage changes in a supply circuit and be substantially free from the contact troubles which are encountered in many types of regulators.

Another object of my invention is to provide a regulator system of the above-indicated character that shall embody a hot-cathode vacuum tube for governing the excitation of a generator in accordance with the voltage obtaining in a supply circuit.

More specifically, my invention embodies a vacuum tube having a hot cathode and a grid anode, the cathode being connected across a supply circuit in accordance with voltage conditions obtaining in the supply circuit and the cathode and the anode being connected in circuit with an exciter generator for governing the excitation of a main generator to maintain a substantially constant voltage in the supply circuit.

In many types of regulators now in service for governing the excitation of a generator to maintain a substantially constant voltage in a supply circuit, a main-contact relay is provided for governing the operation of an exciter generator by short-circuiting, under predetermined conditions, a resistor which is included in the field-winding circuit of the exciter. The main-contact relay embodies a main-control magnet, which is operated in accordance with the supply-circuit voltage and which is adapted to operate directly the main contacts of the relay, and a vibrating magnet which is governed by the main-contact magnet to effect the vibration of the main contacts of the relay. The above type of regulator is very satisfactory, but, at times, some contact troubles are experienced.

In a regulator of the above-indicated type,

which is constructed in accordance with my invention, the main contacts and the vibrating magnets are replaced by a hot-cathode vacuum tube. The hot cathode of the vacuum tube is connected across the supply circuit by means of a main-contact electromagnet which is operated, in the usual manner, in accordance with the voltage obtaining in the supply circuit. The cathode and the anode are connected in circuit with the resistor which is included in the circuit of the exciter-generator field winding so that the resistor is selectively short-circuited in response to variations in the emission current of said tube to vary the excitation of a main generator in accordance with the voltage obtaining in the supply circuit.

The single figure of the accompanying drawing is a diagrammatic view of a regulator system embodying my invention.

Referring to the drawing, a generator 1, embodying an armature 2 and a field magnet winding 3, is connected across a supply circuit embodying conductors 4 and 5. An exciter generator 6, embodying an armature 7 and a field magnet winding 8, is provided for energizing the main field magnet windings 3.

The excitation of the exciter generator 6 is controlled by means of a vacuum-tube regulator 9 which is governed in accordance with the voltage obtaining in the supply conductors 4 and 5. The regulator embodies a hot-cathode vacuum tube 10 having a hot cathode 11 and a grid anode 12, a main-contact electromagnet 13, having an energizing winding 14 connected across the supply conductors 4 and 5, a contact arm 15, which is maintained in a retracted position by means of a spring 16, and a contact member 17, which is adapted to engage the contact member 18 when the arm 15 is moved to a retracted position by means of a spring 16. The regulator further embodies a transformer 19, which is connected across the supply conductors 4 and 5, and a resistor 20 which is connected in series with the exciter field magnet winding 8. The hot cathode of the vacuum tube is connected through the transformer 19 across the supply conductors 4 and 5 by means of the electromagnet 13. The anode of the vacuum tube is connected to one terminal of the resistor 20, and the cathode of the vacuum tube is connected to the other terminal of

the resistor 20 through portions of the winding of the transformer 19.

Assuming the system to be in the position illustrated and the voltage in the supply conductors 4 and 5 to be reduced below normal value, then the spring 16 overcomes the action of the winding 14 to move the contact members 17 and 18 into engagement with each other and connect the hot cathode 11 across the supply conductors 4 and 5. The heating of the cathode 11, in accordance with well-known principles, permits the flow of direct current through the vacuum tube and, consequently, the resistor 20 is short-circuited, inasmuch as the cathode 11 and the anode 12 of the tube are respectively connected to the terminals of the resistor. Accordingly, the excitation of the auxiliary generator 6 is increased to raise the value 20 of the voltage supplied by the main generator 1 to the supply conductors.

In case the voltage of the supply conductors is raised above normal value, the electromagnet 13 is operated to break the circuit of the hot cathode and thus remove the short circuit across the resistor 20 and reduce the excitation of the auxiliary generator 6.

In the system above described, the contact members 17 and 18 are at no time subjected to excessive current or to excessive inductive discharges and, therefore, a regulator of this type is substantially free from the many contact troubles which are usually experienced in regulator systems.

Modifications in the system and arrangement and location of parts may be made within the spirit and scope of my invention, and such modifications are intended to be covered by the appended claims.

I claim as my invention:

1. In a regulator system connected to a supply circuit, a resistor, a vacuum tube connected to said resistor having a hot cathode and a grid anode, and a relay operated in accordance with the voltage obtaining in the supply circuit for connecting said cathode across the supply circuit to control said resistor.
2. In a regulator system connected to a supply circuit, a translating device, a hot-cathode vacuum tube operatively associated

with said translating device, and means adapted to short-circuit the translating device, said means comprising a relay for energizing the tube in accordance with the voltage obtaining in the supply circuit. 55

3. In a regulator system connected to a supply circuit, a vacuum tube having a hot cathode and a grid anode, a transformer 60 connected across the supply circuit, a relay connected across the supply circuit and adapted to connect said cathode in circuit with the transformer, and a translating device connected in circuit with the cathode 65 and the anode of the vacuum tube.

4. In a regulator system, the combination with a supply circuit, a generator connected to the supply circuit, an auxiliary generator having an armature and a field winding for 70 exciting the main generator, and a translating device connected in circuit with the field winding of the auxiliary generator, of a vacuum tube connected in circuit with said translating device and having a hot cathode 75 and a grid anode, and a relay connected across the supply circuit and adapted to connect the cathode of said tube across the supply circuit whereby the vacuum tube, the translating device, and the exciter connected thereto co-operate to maintain a substantially constant voltage in the supply circuit. 80

5. The combination with a supply circuit, and a generator connected to the supply circuit, of a hot-cathode vacuum tube, and 85 means for varying the excitation of said generator to maintain a substantially constant voltage in the supply circuit comprising means for intermittently heating the cathode of said tube. 90

6. In a regulator system, a generator connected to a supply circuit, a hot-cathode vacuum tube, means for intermittently heating the cathode of said tube in accordance with an electrical condition obtaining in the 95 supply circuit, and means controlled by said vacuum tube for governing the excitation of said generator to maintain substantially constant a characteristic of the supply circuit. 100

In testimony whereof, I have hereunto subscribed my name this 27th day of August, 1918.

FRANK CONRAD.
